[57] CLAIM

[21] Appl. No.: 67,737

The ornamental design for a mercury vapor light base for exterior lighting fixture, as shown and described.

[22] Filed: Mar. 11, 1997

DESCRIPTION

[51] LOC (6) Cl. 26-03

FIG. 1 is a top isometric view of a mercury vapor light base for exterior lighting fixture showing my new design;

[52] U.S. Cl. D26/71

FIG. 2 is a bottom isometric view thereof;

[58] Field of Search D26/24, 67-70, D26/72, 87, 92, 142; 362/147, 153, 362, 431, 432

FIG. 3 is a top plan view thereof;

[56] References Cited

FIG. 4 is a bottom plan view thereof;

U.S. PATENT DOCUMENTS

FIG. 5 is a back elevational view thereof;

D. 184,007 12/1958 Corwin D26/71

FIG. 6 is a front elevational view thereof; and,

D. 313,483 1/1991 Blake D26/71

FIG. 7 is a side elevational view thereof with other elements of a mercury vapor light shown in phantom for illustrative purposes only and forming no part of the claimed design.
